(57) **CLAIM**

The ornamental design for a note and clip, as shown and described.

DESCRIPTION

FIG. 1 shows a perspective view of a first embodiment of a design of a note and clip.

FIG. 2 shows a right-side view of FIG. 1. A left-side view is a mirror image of the right-side view.

FIG. 3 shows another perspective view of FIG. 1.

FIG. 4 shows a front view of FIG. 1. A back view is a mirror image of the front view.

FIG. 5 shows the right-side view of FIG. 1. A left-side view is a mirror image of the right-side view.

FIG. 6 shows a back view of FIG. 1. The front view is a mirror image of the back view.

FIG. 7 shows a top view of FIG. 1.

FIG. 8 shows a bottom view of FIG. 1.

FIG. 9 shows a perspective view of a second embodiment of a design of a note and clip.

FIG. 10 shows a right-side view of FIG. 9. A left-side view is a mirror image of the right-side view.

FIG. 11 shows another perspective view of FIG. 9.

FIG. 12 shows a front view of FIG. 9. A back view is a mirror image of the front view.

FIG. 13 shows the right-side view of FIG. 9. A left-side view is a mirror image of the right-side view.

FIG. 14 shows a back view of FIG. 9. A front view is a mirror image of the back view.

FIG. 15 shows a top view of FIG. 9; and,

FIG. 16 shows a bottom view of FIG. 9.

The surfaces of the note are entirely unclaimed except for the edge lines that are shown as solid lines. The broken-line features in the figures are for illustrative purposes only and form no part of the claimed design.
